ELECTRONIC FLASHER SYSTEM

Helmer T. Pederson, Solana Beach, Calif., assignor to Bill Jack Scientific Instrument Co., Solana Beach, Calif., a corporation of California

Application March 15, 1957, Serial No. 646,488

8 Claims. (Cl. 315—209)

This invention relates to electronic flasher systems for signal lights for various purposes, but primarily in aircraft lighting and warning systems.

The primary object of this invention is to provide a flasher system for signal lights in which there are no moving elements, thus assuring more efficient operation and longer life.

A more specific object of this invention is to provide a free running static flasher system for signal lights in which the flashing rates are determined solely by the electrical components of the system.

Another object of this invention is to provide a flasher system for signal lights which is operable over a wide range of voltages and in which the flashing rate is independent of voltage.

A further object of this invention is to provide a flasher system for signal lights in which the electrical components in the system may be replaced to derive flashing rates of different durations.

Another object of this invention is to provide a flasher system for signal lights which requires no maintenance or service time.

With the foregoing and other objects in view the invention resides in the following specification and appended claims certain embodiments thereof being illustrated in the accompanying drawing in which:

Figure 1 is a schematic circuit diagram of the flasher system comprising the invention.

Figure 2 is a schematic circuit diagram of a modified form of the invention as illustrated by Figure 1.

Referring now more particularly to Figure 1, it will be noted that the flasher system includes a pair of transistor units 1 and 2. Transistor 1 includes a collector 3, an emitter 4 and a base 5. Transistor 2 includes a collector 6, an emitter 7 and a base 8. Emitters 4 and 7 are connected through resistances 9 and 10 respectively to the positive terminal 11 of a source of D.C. potential (not shown).

The base 5 of transistor 1 is connected to a parallel circuit including a condenser 12 and a resistance 13 and this R-C. circuit is grounded at 14 through an incandescent lamp 15. The base 8 of transistor 2 is connected to a parallel circuit including a condenser 16 and resistance 17, and this R-C. circuit is grounded at 14 through an incandescent lamp 18.

The collector 6 of transistor 2 is connected to a point 19 in the line 20 between the lamp 15 and the R-C. circuit of transistor 1. The collector 3 of transistor 1 is connected to a point 21 in the line 22 between the lamp 18 and the R-C. circuit of transistor 2.

The operation of the system is determined by the two operating modes of each transistor, namely saturation and cutoff. Since the transistors are in an unstable initial condition, the application of a line voltage at positive terminal 11 will result in the collector, emitter and base drawing current. The base 5 current will charge condenser 12 and this current will be reflected as a voltage drop across lamp 18. The condenser 16 is also being

2

charged during this initial voltage application to terminal 11 from the base 8 of transistor 2.

The voltage drop across lamp 18 and the charge on condenser 16 are additive, and as the transistor 1 continues to draw current the voltages at base 8 on transistor 2 will be driven to a cutoff condition with respect to transistor 2. The resistor 17 determines the time for the charge to leak off condenser 16, and at the moment the base 8 begins to conduct again, the voltage across lamp 15 will begin to increase, building up a combined voltage with condenser 12 at base 5 to place transistor 1 in a cutoff condition. Transistor 2 will then proceed to saturation and will remain in this state due to the fact that with transistor 1 in a cutoff condition, the voltage on lamp 18 has been removed, and the current required to recharge condenser 16, after discharge through resistance 17, will continue to be drawn from the current flow at the base 8. When the charge on condenser 12 has leaked off through resistance 13 the base 5 begins to conduct again and the voltage across lamp 18 will begin to increase and the cycle will repeat. Thus it will be apparent to one skilled in the art that the lamp 18 will be illuminated when transistor 1 is operating in its saturation mode, while simultaneously lamp 15 will be dark with transistor 2 operating in its cutoff condition. As the cycle reverses, the illumination of lamps 15 and 18 reverses. The R-C circuit for transistor 2 will therefore determine the light and dark periods for lamp 15 while the R-C circuit for transistor 1 will determine the same periods for lamp 18. By varying the resistor and condenser values connected to each transistor, the time of the light and dark periods may be altered to suit various applications.

The resistors 9 and 10 are emitter bias resistors and are utilized to leave sufficient voltage across the collector and the emitter of each transistor when in the cutoff condition to enable the transistor to operate as a trigger when its base begins to draw current. The values of resistors 9 and 10 are dependent on the types of transistors used and the minimum voltages these transistors need to conduct.

It will be obvious to one skilled in the art that this system is free running in character and that the lamps will continue to flash as long as the system is energized. It will also be obvious that no moving parts are required to control the flashing of the lamps and that the system is static in character.

The circuit of Figure 2 is identical in operation to that of Figure 1. However, the lamp 15 of Figure 1 has been replaced by an equivalent resistance 23 to arrive at a suitable circuit where only one flashing lamp is desired. While other lamps may be utilized, the present invention has been practiced with lamps having an equivalent resistance of 680 ohms.

Thus it should be apparent to one skilled in the art that the flasher system of this invention provides a fully automatic cycling operation to control the light and dark periods of one or more lamps without resorting to any controls involving the use of moving parts.

I claim:

1. A free running static flasher system comprising a pair of transistors, a lamp in circuit with each transistor, means to apply a positive potential to the transistors, control means connected to each transistor to determine the cutoff period of each transistor, and means cross-connecting each transistor to the lamp circuit of the other transistor, each said lamp being energized or de-energized in accord with operating conditions of the transistor to which it is cross-connected.

2. A free running static flasher system comprising a pair of transistors, each including an emitter, a collector and a base, a lamp in circuit with the base of each trans-

sistor and ground, means to apply a positive potential to the emitter of each transistor, control means connected in the lamp circuit to the base of each transistor between the lamp and the base to determine the cutoff period of each transistor, and means cross-connecting the collector of each transistor to the lamp circuit of the other transistor at a point between the lamp and the control means, each said lamp being energized or de-energized in accord with the operating condition of the transistor to which it is cross-connected.

3. A free running static flasher system comprising a pair of transistors each including an emitter, a collector and a base, a lamp in circuit with the base of each transistor and ground, circuit means to apply a positive potential to the emitter of each transistor, resistance means connected in said emitter potential circuit to positively bias each transistor, control means connected in the lamp circuit to the base of each transistor between the lamp and the base to determine the cutoff period of each transistor, and means cross-connecting the collector of each transistor to the lamp circuit of the other transistor at a point between the lamp and the control means, each said lamp being energized or de-energized in accord with the operating condition of the transistor to which it is cross-connected.

4. A free running static flasher system comprising a pair of transistors, a lamp in circuit with each transistor, circuit means to direct a positive potential to each of the transistors, resistance means connected in the potential directing circuit means of each transistor to positively bias each transistor, control means connected to each transistor to determine the cutoff period of each transistor, and means cross-connecting each transistor to the lamp circuit of the other transistor, each said lamp being energized or de-energized in accord with operating conditions of the transistor to which it is cross-connected.

5. A free running static flasher system comprising a pair of transistors, each including an emitter, a collector and a base, a lamp in circuit with the base of the first transistor and ground, a resistor in circuit with the base of the second transistor and ground, means to apply a positive potential to the emitter of each transistor, control means connected in the lamp circuit to the base of the first transistor between the lamp and the base and between the resistor and the base of the second transistor to determine the cutoff period of each transistor, means cross-connecting the collector of the second transistor to the lamp circuit of the first transistor at a point between the lamp and the control means, and means cross-connecting the collector of the first transistor to the resistor circuit of the second transistor at a point between the resistor and the control means, the said lamp being energized or de-energized in accord with the operating condition of the second transistor.

6. A free running static flasher system comprising a pair of transistors, each including an emitter, a collector and a base, a lamp in circuit with the base of the first transistor and ground, a resistor in circuit with the base of the second transistor and ground, circuit means to direct a positive potential to the emitter of each transistor, resistance means connected in the potential directing circuit means of each transistor to positively bias each transistor, control means connected in the lamp circuit to the base of the first transistor between the lamp and the base and between the resistor and the base of the second transistor to determine the cutoff period of each transistor, means cross-connecting the collector of the second transistor to the lamp circuit of the first transistor at a point between the lamp and the control means, and means cross-connecting the collector of the first transistor to the resistor circuit of the second transistor at a point between the resistor and the control means, the said lamp being energized or de-energized in accord with the operating condition of the second transistor.
7. A free running static flasher system comprising a pair of transistors, each including an emitter, a collector and a base, a lamp in circuit with the base of each transistor and ground, circuit means to apply a positive potential to the emitter of each transistor, a resistor-condenser parallel circuit control means series connected in the lamp circuit to the base of each transistor between the lamp and the base to determine the cutoff period of each transistor, and means cross-connecting the collector of each transistor to the lamp circuit of the other transistor at a point between the lamp and the resistor-condenser control means, each said lamp being energized or de-energized in accord with the operating condition of the transistor to which it is cross-connected.
8. The invention according to claim 7 wherein resistance means is included in the potential applying circuit means for each transistor to positively bias each transistor to thereby condition each transistor to act as a trigger means.
